205,836

THREE-WHEELED SWAMP BUGGY WITH FORWARD CAB

Ward T. Commons, Halsey, Oreg.

Filed Oct. 18, 1965, Ser. No. 87,576

Term of patent 14 years

(Cl. D14—3)

Fig. 1.

Fig. 2.

*Fig. 3.Fig. 4.*FIGURE 1 is a side elevational view of a three-wheeled swamp buggy with forward cab showing my new design.

FIGURE 2 is a top plan view thereof.

FIGURE 3 is a front end elevational view thereof.

FIGURE 4 is a rear end elevational view thereof.

I claim:

The ornamental design for a three-wheeled swamp buggy with forward cab, substantially as shown.

References Cited by the Examiner

UNITED STATES PATENTS

D. 191,702 11/1961 Keeber et al. ----- D14—3

OTHER REFERENCES

Dana Digest, received Sept. 21, 1964, page 3, "Teracruzer," bottom of page.

Popular Science, November 1960, page 78, cross-country tractor, bottom of page.

WALLACE R. BURKE, Primary Examiner.

CONRAD A. BOUSQUET, WILLIAM N. WERTMAN,
Assistant Examiners.